(57) **CLAIM**

The ornamental design for a pocket tool with tape measure, as shown and described.

DESCRIPTION

FIG. 1 is a front right perspective view of a pocket tool with tape measure showing the new design in a closed configuration;

FIG. 2 is a back right perspective view thereof;

FIG. 3 is a left elevation view thereof;

FIG. 4 is a front elevation view thereof;

FIG. 5 is a top plan view thereof;

FIG. 6 is a back elevation view thereof;

FIG. 7 is a right elevation view thereof;

FIG. 8 is a bottom plan view thereof;

FIG. 9 is a front right perspective view thereof showing the pocket tool with tape measure in an opened configuration;

FIG. 10 is a back left perspective view thereof;

FIG. 11 is a back right perspective view thereof;

FIG. 12 is a front right perspective view of an alternate embodiment of the pocket tool with tape measure in an opened configuration; and,

FIG. 13 is a back right perspective view thereof.

The broken lines depict environmental subject matter, are for illustration only, and form no part of the claimed design.

1 Claim, 2 Drawing Sheets
